United States Patent Office.

JAMES C. STRONG AND LUTHER C. MCNEAL, OF BUFFALO, NEW YORK; SAID LUTHER C. MCNEAL ASSIGNS HIS RIGHT TO SAID JAMES C. STRONG.

Letters Patent No. 94,984, dated September 21, 1869.

FIRE-PLACE.

The Schedule referred to in these Letters Patent and making part of the same.

To all whom it may concern:

Be it known that we, JAMES C. STRONG and LUTHER C. MCNEAL, of the city of Buffalo, county of Erie, and State of New York, have invented a new and improved Mode of Supplying the Gases Evolved by Burning Coal in a Fire-Place with Air, from the back or sides of the fire-place, thus creating more perfect combustion, thereby obtaining more heat from the same amount of fuel, by consuming the gases that would otherwise pass up the chimney.

Also, a new and improved form of fire-place, composed of a deep space or chamber above and in rear of the fire-basket, in combination with an inclined corrugated top, inclining upward from the back toward the front; and we do hereby declare that the following is a full and exact description thereof, reference being had to the accompanying drawings, and to the letters of reference marked thereon.

The nature of our invention consists in constructing an air-chamber, E, attached to the back or sides of the fire-place, which, being supplied with air by means of two apertures D D, under the fire-basket, discharges it into the back of the fire-place, by means of holes F F, perforated through the back of the fire-place, thus supplying the gases evolved by the burning coal in the grate with sufficient air to cause their complete combustion.

To enable others to make and use our invention, we will proceed to describe its construction and operation, reference being had to the accompanying drawings.

We construct the air-chamber E, Figure 5, of iron or other suitable material, making it of sufficient depth to conduct the requisite quantity of air from the apertures D D to the perforations F F in the back of the fire-place C, Figure 3, the dimensions being regulated by the size of the fire-place.

The front of this air-chamber being placed directly against the back of the fire-place C, as shown in Figure 4, its top, back, and sides being completely enclosed with plaster, renders it perfectly air-tight, so that none of the air drawn through the apertures D D can escape, except through the perforations F F in the back C of the fire-place, fig. 3, the heat causing

a continual passage of air into the apertures D D, through the air-chamber E into the rear of the fire, through the perforations F F, supplies the gases in the rear of the fire with oxygen, thus causing their perfect combustion, adding greatly to the amount of heat derived from the coal in two ways—

First, by igniting the gases that would otherwise pass up the chimney; and

Secondly, heat being much more easily moved than smoke, the slight current pouring into the rear of the fire through the perforations F F, forces the heat directly into the room, while it does not prevent the smoke from passing up the chimney, thus economizing fuel.

The air-chamber E or perforations F F can be attached to or made in the back or sides of the fire-chamber, as convenience may dictate.

We construct the fire-place or chamber of fire-brick, soapstone, or other appropriate material, with two cheeks A A, a back, C, and corrugated top B.

It is so constructed that the back C recedes from the bottom toward the top, thus forming the chamber larger at the top than at the bottom.

We construct an inclined corrugated top, B, ascending from the back C toward the front of the fire-chamber, by means of which the gases are very much retarded in their passage toward the chimney, giving them more time to mingle with the oxygen coming through the perforations F F, and by its inclination aiding materially in reflecting the heat into the room.

We claim as our invention, and desire to secure by Letters Patent—

1. The fire-place A, with its sloping perforated back, in combination with the inclined corrugated top, constructed and arranged substantially as described.

2. In combination with the subject-matter of the foregoing claim, the air-inlet passages D and F and chamber E.

JAMES C. STRONG.
LUTHER C. MCNEAL.
